UNITED STATES PATENT OFFICE.

CHRISTIAN PETERSEN, OF SIOUX CITY, IOWA.

REPAIRING OVERSHOE HEEL.

Application filed February 7, 1927. Serial No. 166,499.

My invention relates to the art of repairing overshoes and has for its object to provide a method especially adapted to the repairing of ladies' overshoe heels where the heel has become badly worn.

More particularly, it is my object to provide a method by which the heel can be repaired so as to retain the same size and contour both on the outside and inside as the contour of the original heel.

A still further object is to provide a method by which the retaining of the original contour is assured in a simple manner which does not require extraordinary skill upon the part of the workman.

Another object of the invention is to provide a repair heel for use in connection with the method of my invention.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a side elevation of a lady's overshoe, the heel being shown worn to such an extent that ordinary methods of repair will not suffice to replace it.

Fig. 2 is a rear view of the same.

Fig. 3 is a longitudinal sectional view through the overshoe, showing the heel removed according to my invention, the removed portion being illustrated in broken lines.

Fig. 4 is a transverse sectional view through the heel, showing the same.

Fig. 5 is a longitudinal sectional view through the overshoe, illustrating the attachment of the repair heel.

Fig. 6 is an inverted plan view of the overshoe with the repair heel attached.

Fig. 7 is a perspective view of the repair heel.

The ordinary overshoe repair heel, now found in general use, comprises a flat slab of rubber with a semi-cup shaped flap of rubber, at the rear end. Such a heel has been found satisfactory to a certain extent in repairing men's overshoes of which the heel is comparably shallow and flat. The flat slab of rubber is cemented and nailed to the old heel which has simply been roughened and cleaned to receive it and the

flap is cemented to the rear surface of the overshoe projecting upwardly from the base of the heel.

I have attempted to use the same method of repairing for ladies' overshoes but find it very ineffective and unsatisfactory. Due to the much smaller surface of the lady's heel, its more rounded shape and the fact that wearing is likely to remove the rubber at the rear corner of the heel to a level beyond the inner surface thereof, it is very difficult ordinarily to secure a water-tight joint between the old heel and the repair heel.

A great majority of the overshoes of which the heels need repairing are brought to the repairman in such a condition as that shown in Fig. 1 of the drawings. It will be noted there that the rear portion of the heel has been worn to such an extent that a hole has been worn clear through the heel, as indicated at 10 in Fig. 2, the hole extending above the inner surface of the heel indicated at 11. It is obvious that to attach such a flat slab to the bottom of such a heel would not only be impractical but would produce a joint which probably would not be watertight, the height of the heel would be increased, the thickness of the slab and the appearance of the completed job would be far from satisfactory.

In order to eliminate this objection of increasing the thickness thereof, the first step of my process comprises the removal of the heel proper which has been indicated by the reference character 12. The repair heel is shown at Fig. 7 and comprises a base 13 and a flap having the sides 14, the rear wall 15 and the front wall 16 all formed integrally with the base 13. The upper edge of the side walls 14 and 15 are curved to conform with the base line 17 of the overshoe and this line is cut away as at 18 to meet the edge of the front wall 16 which extends under the overshoe. The cup-shaped flange which is thus formed by the walls 14, 15 and 16 is shaped to fit the side walls 19, the rear portion of the instep wall 20 and the rear portion of the heel wall 21 of the overshoe.

Returning to the step of cutting away the old heel of the overshoe, it will now be seen that it would be very difficult to insert the repair heel over any projecting portions of the original heel such as the rolled edges 22. The line of cut is therefore made above these rolled edges as at 23 so as to entirely

remove them from the overshoe, the projecting point 24 being trimmed down with a knife.

The rolled edges 22 do not extend across the forward edge of the heel, there being, however, a definite division line between the wall 20 and the heel proper 12 as at 25. In removing the old heel, the cut is made directly at this division line and thence extended upwardly to bring it above the rolled edges 22. The object in cutting the wall 20 at the division line 25 is to leave a means for gauging the proper position of the repair heel relative to the overshoe. An inspection of the drawings shows that the lower edge of the flap thus remaining will contact with the inner surface of the heel base 13 so as to position said inner surface in exactly the same position originally occupied by the heel portion 12. The walls 16 and 15 being inclined to each other, as indicated by the broken lines 26 and 27, respectively, it will now be seen that the position of the forward corner of the heel base 13 being accurately determined, the engagement of the rear wall 15 with the wall 21 of the overshoe will serve to properly position the remainder of the repair heel, even though the side walls 19 and rear wall 21 are cut away at a substantial distance above the base of the heel.

While thus gauging first the position of the forward corner of the repair heel and then allowing the heel to contact snugly with the side and rear walls of the overshoe, the workman is assured of getting a snug fit between all portions of the side walls of both overshoe and repair heel and the cemented surfaces will readily adhere to each other. Perfect union is had between the cemented surfaces simply because they fit each other. If there were no gauge to accurately adjust the relative positions of heel and overshoe, it would be easy to apply the heel slightly out of position and to stretch the contiguous walls sufficiently to obtain a contact. This would require, however, considerable time of the workman in pressing the parts together and the union would not be as perfect.

It will be understood that the smooth coating of rubber which is found around the base of the overshoe and which is defined by the line 17 is cleaned and roughened preparatory to the cementing of the repair heel in place. After the heel has been applied with sufficient cement to cause adhesion, a line of stitching is run, as indicated by the dotted line 28 in Fig. 5. Another line of stitching closer to the base of the heel may be added if desired.

The repair heel having sides which flare outwardly in all directions is an improvement over the old type of repair heel in that after the heel has been attached, the strain

communicated between heel and body of the overshoe will be received in any direction by one of the side walls of the repair heel. The strain between heel and body of the overshoe is ordinarily a pushing strain in which there is a tendency for the overshoe to wedge more tightly into the heel. Accompanying this, there is the usual side strain or longitudinal strain caused by the shuffling of walking. The resultant of these two strains in any direction will always be opposed by the contact of one of the side walls of the repair heel against the body of the overshoe and consequently it will be practically impossible to rip the heel loose in ordinary usage.

The heel being in exactly the same position as the original heel, the repair will cause no discomfort to the wearer, the height of the foot from the ground will remain the same and the appearance of the overshoe will be almost the same as in the original shoe. The upper edge of the flaps 14 being shaped to fit the line 17, the only point at which the union of repair heel and overshoe will be apparent is along the edges 18.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. The art of repairing an overshoe having a comparatively deep heel including forward and rear walls inclined downwardly and toward each other and a heel proper including rolled side edges extending above the inner surface of the heel proper comprising the following steps: severing the forward wall of the heel at the division line between the heel proper and said forward wall, thence cutting upwardly and rearwardly above the rolled edges and thence applying a repair heel including inclined forward and rear walls joined by side walls shaped to fit the exterior surface of the original heel and securing said repair heel in place with the lower extremity of the forward wall of the original heel engaging substantially the base of the repair heel.

2. The art of repairing an overshoe having a comparatively deep heel including forward and rear walls inclined downwardly and toward each other and a heel proper including rolled side edges extending above the inner surface of the heel proper comprising the following steps: severing the forward wall of the heel at the division line between the heel proper and said forward wall, thence cutting upwardly and rearwardly above the rolled edges and thence applying a repair heel including inclined for-

ward and rear walls joined by side walls shaped to fit the exterior surface of the original heel and securing said repair heel in place.

- 5 3. The art of repairing an overshoe including a heel of substantial depth and having forward and rear walls inclined downwardly and toward each other and a heel proper including rolled side edges extending 10 above the inner surface of the heel proper including the following steps: severing the heel proper from the remainder of the heel on a line above the rolled edges thereof and

applying a repair heel including a heel base and forward, rear and side walls extending 15 continuously therearound and shaped to fit the walls of the original heel, thence cementing said repair heel to the walls of the original heel in a position identical with that of the original heel and thence running a line 20 of stitching to secure the side walls of the repair heel to the side walls of the original heel.

Signed this 31st day of January, 1917, in the county of Woodbury and State of Iowa.

CHRISTIAN PETERSEN.
